FRANK B. ALLEN, OF NARBERTH, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA.

SECTIONAL CATENARY BUNKER.

Application filed August 6, 1924. Serial No. 730,548.

This invention relates to hoppers, particularly those of the so-called catenary type, wherein the hopper is supported from its top edges and has curved walls following, in general, the line of a catenary curve. The invention also relates to a hopper composed of a plurality of independently removable, overlapping sections having slidable contact with each other and supported by tension members suspended from their ends. It also relates to a hopper of the catenary type having sectional cast iron walls and a steel supporting structure on the exterior thereof. It further relates to the construction of a substantially water tight, durable, unlined hopper having sectional walls and adapted to change its shape to a limited extent when carrying a load.

In the drawings attached hereto and forming a part of this specification, and in which I have illustrated one embodiment of my invention—

Figure 1 is a fragmentary perspective view of a hopper of the catenary type embodying my invention.

Fig. 2 is a fragmentary enlarged vertical section of the bottom part of the hopper shown in Fig. 1.

Fig. 3 is a fragmentary vertical section taken near the top of the side walls of the hopper shown in Fig. 1, showing certain parts in enlarged detail.

Fig. 4 is an enlarged fragmentary sectional view taken on a horizontal plane through the side walls near the top of Fig. 1.

Figure 5 is a vertical section taken on line 5—5 of Fig. 1, and

Figure 6 is an enlarged fragmentary sectional view taken on line 6—6 of Fig. 5.

In the drawings, 1 designates as an entirety a hopper of the catenary type, that is, having side walls suspended from their ends and curved therebetween preferably, though not necessarily, in the form of a catenary curve.

The curved side walls of hopper 1 are designated by numeral 2, while 3 indicates straight end walls. The hopper 1 is supported by a frame-work consisting of uprights 4, top end

members 5 and top side members 6. From end members 5 angle bars 7 are suspended, while to the side members 6 bands 8 are secured, the bands 8 being curved intermediate their ends substantially as shown and with either end secured to a member 6. I prefer to use steel for the angle bars 7 and bands 8 for reasons which will appear hereinafter.

The ends walls of the hopper of Fig. 1 are formed by securing to the suspended angle bars 7, wall sections 9, which sections are substantially rectangular and are provided with outwardly extending flanges along the peripheral edges so shaped as to cooperate with similarly formed flanges on adjacent plates. These plates 9 may be secured to the member 7 by various means but I prefer to secure them by means of bolts 10, which pass through perforations 11 in the angle bars 7, the heads of the bolts being removably interlocked with correspondingly shaped bolt lugs 12 on the outside of plates 9. It will be understood that the lugs 12 are composed of a wall portion 13 integral with but spaced apart from the body of the plate 9 and having a slot 14 cut in one side thereof which slot is narrower than the width of the bolt head, so that the shank of the bolt may slide therein but the head of the bolt may not pass therethrough. Corner members 15 are secured to the lower or free ends of the angle bars 7 and are bent to correspond with the curvature of the side walls of the hopper. The plates 9 are secured to members 15 substantially in the manner as described for plates 9 and bars 7. Strengthening tie plates 16 extend across the end walls of the hopper and are secured to the angle bars 7, and are connected with side tie plates 17 which act as supports for the side walls 2 of the hopper to limit the outward movement of walls 2.

Reference to Figs. 5 and 6 will make clear the interlocking arrangement of the end plates 9. Fig. 5 shows the formation of the upper and lower edges of plates 9 with each plate having along its lower edge a flange which overlaps the upstanding flange of the plate next therebelow and engages on the in-

side of such flange in a manner to cause water passing down the wall to remain inside the hopper and not leak out through the horizontal joints between the plates. In Fig. 6 it will be noted that the plates 9 have correspondingly formed flanges 9^a and 9^b on their vertical edges and that the vertical edges of adjacent plates are located lengthwise of the angle bars 7 so that these bars effectively 10 constitute a closure of the small space between adjacent plates, thereby preventing leakage of water through the vertical joints between the plates. Due to the construction of the end walls 3 including the tie plates 16 these walls are substantially rigid even when the side walls tend to take on different shapes under load.

The side walls 2 of hopper 1 are preferably composed of wall sections 18 which are substantially rectangular in cross section and which have outwardly projecting flanges on their peripheral edges. The plates 18 for use at points near the top of the hopper or at certain points therebelow may be substantially plane, while the plates 18 constituting the bottom portions of the walls where there is considerable curvature, are curved substantially as shown in Fig. 2.

The vertical ends of plates 18 are provided with cooperating flanges 19 and 19^a resembling, for practical purposes, the flanges on the vertical ends of plates 9, while the upper edge of each plate 18 is provided with a flange 20 having a convex inner surface 21. The lower horizontal edge of each plate 18 is provided with a flange 22 having a concave outer surface 23 to project over and substantially engage the convex inner surface 21 on the plate therebelow, the surfaces 21 and 23 being preferably formed with substantially the same radius so that two adjacent plates 18 may be moved relatively to each other without effecting the initial close fitting contact between flanges 20 and 22. It will be observed that flange 22 projects over the inner surface of flange 21 at all times, thereby preventing leakage of water through the horizontal joints between the plates in much the same manner as has already been described 50 in connection with the horizontal edges of end plates 9 represented by Figs. 5 and 6.

Side sections or plates 18 are supported on the inner sides of bands 8, the bands being preferably located over the vertical edges of 55 the plates to insure a substantially water tight junction of the plates. Each plate 18 is provided with one or more bolt lugs 24 resembling the bolt lugs 12 on end plates or sections 9 and adapted to receive bolts 25 removable in the same manner as bolts 10 are held in lugs 12. The means for securing sections 18 in contact with bands 8 preferably comprise bolts 25 and plates 26 disposed on the outer side and transversely of bands 8,

each plate 26 being provided with holes on 65 either side of bands 8 to receive the bolts 25. When nuts 27 are screwed onto the bolts 25 they clamp the bands 8 between wall sections 18 and plate 26, thereby securing the wall sections firmly in place.

The bands 8 which are preferably formed of steel and are capable of being bent during installation or when the hopper is subjected to load thus carry the wall sections 18 firmly secured thereto but permit limited movement 75 between the sections so that the hopper may change its shape or its curvature to a limited extent, when subjected to load.

The wall sections or plates 9 and 18 are preferably formed of cast iron since this material is more durable in the presence of acidulated water, such for example as is present in coal and because of this property, I find it unnecessary to use any lining material for the hopper. The flanges 9^a, 9^b and 19 and 19^a 85 on the wall sections cooperate to prevent leakage of water between the sections and particularly when the spaces between the adjacent plates are filled with a material which quickly rusts the iron and forms an effective seal against the passage of water therethrough. The bands 8 and angle bars 7 may be composed of steel because of the substantially water tight nature of the walls 2 and 3, it being understood that steel is attacked readily by acidulated water. It is preferable 90 to use steel because it is so much stronger than cast iron or other materials suitable for use in hopper construction.

It will be noted that the angle bars 7 and 100 bands 8 which afford the entire support for the hopper walls are always in tension and are not subjected to compression no matter how the hopper is loaded. Since the centers of curvature of the surfaces 21 and 23 lie in bands 8, any relative movement of plates 18 will be accompanied by a curving of bands 8 substantially free of any bending moment. For these reasons lighter parts may be utilized than has been possible heretofore and consequently the resulting hopper is considerably lighter than any in existence prior to my invention. A further fact which results in the construction of a light hopper is the elimination of the customary hopper lining material which necessitated the provision of 110 correspondingly greater strength in the supporting members.

It will be understood that in the present construction, the side walls 2 tend to change their shape under load, the change being a maximum at a point midway between the end walls 3 and a minimum at the junctions with the end walls provided the load is applied uniformly.

It will also be understood that, by reason of the formation of flanges on the wall plates 9 and 18, it is easy to remove any plate 9 or

18 from the wall and insert another one independently of all the remaining plates. This is of advantage in repair or maintenance work where it may be necessary to substitute a new 5 plate for a damaged or broken plate.

Although I have described my invention as embodied in a hopper having curved side walls, it will be obvious to those skilled in the art that it is applicable to hoppers variously 10 constructed, where a limited amount of relative movement between the wall sections is desired and where the members supporting the wall sections are in tension. Accordingly, I do not desire to have my invention limited to 15 the modification shown but to have it construed as broadly as is indicated by what is claimed.

What I claim is:

1. A hopper comprising a sheathing composed of a plurality of rigid, relatively movable sections, and a suspension frame sufficiently flexible to permit the sheathing to assume a free curve in vertical cross section under weight of the sheathing.

25 2. A hopper having walls capable of limited movement when subjected to load comprising curved, wall supporting members and a wall composed of independently removable sections carried thereby, each section having 30 its edges shaped to engage slidably at all times the correspondingly shaped edges of the sections adjacent thereto, and means securing the said members and sections together while permitting limited relative movement 35 of the sections with respect to each other.

3. A hopper having side walls composed of wall supporting, tension members and wall sections carried thereby, each section of the said wall being provided at its lower side edge 40 with a suitably shaped surface to cooperate with the inner surface at the top edge of the adjacent plate therebelow with water tight, 45 slidable engagement.

4. A hopper having walls composed of 45 wall supporting steel members suspended from their ends and cast iron wall plates carried on the inner side of the said steel members, the plates having overlapping, substantially water proof engagement with each 50 other and with the said members.

5. A hopper having curved walls comprising curved, wall supporting tension members capable of changing the form of their curvature when subjected to load, and wall sections 55 supported by the said members and adapted to permit change of curvature of the said members substantially free of any bending movement in said sections.

6. A hopper having curved walls comprising curved, wall supporting tension members capable of changing the form of their curvature when subjected to load, and sectional walls supported by the said members, each 60 wall section having slidably engaging con-

tact with the sections adjacent thereto where- 65 by change of curvature of the said tension members when subjected to load is permitted.

7. A hopper of the catenary type comprising wall supporting members having the general curvature of a catenary curve and capable of assuming different curvatures when subjected to load, and a sectional wall carried by the said members, each section of the wall having slidable, liquid sealing contact with the sections adjacent thereabove and therebelow and means securing the said sections in water sealing contact at their ends with the said tension members.

8. A hopper having curved said walls comprising members in the form of bands suspended from their ends, wall sections supported by the bands and means securing the sections in contact with the bands, the said securing means comprising a plate located on the outside and extending transversely of the 80 said bands, and members passing through the plate on either side of the band and secured to the wall sections.

9. A hopper having curved side walls comprising members in the form of bands suspended from their ends, wall sections supported by the bands and means securing the sections in contact with the bands, the said securing means comprising a plate extending transversely, and on the outside of the band 90 and having holes on either side of the band, bolts passing through the holes, the heads of the bolts having interlocking engagement 95 with the said sections.

10. As a new article of manufacture, a 100 wall section for a hopper comprising a substantially rectangular body having peripheral flanges on all sides thereof adapted to cooperate with corresponding flanges of similar sections, the flange on one side having a 105 concave outer surface and the flange on the opposite side thereof having a convex inner surface, the curvature of the said concave and convex surfaces being approximately equal.

11. A hopper having walls composed of 110 sections, the edges of said sections being provided with flanges for interlocking with adjacent sections, one of said interlocking flanges having a concave outer surface and the flange interlocking therewith having a 115 convex inner surface, the curvature of said surfaces being substantially the same, and the center curvature lying between said flanges.

12. A hopper comprising a plurality of 120 walls each composed of a plurality of relatively movable sections, and a flexible frame including catenary members supporting said walls for such relative movement.

13. A hopper comprising a plurality of 125 relatively movable cooperating wall members, and a catenary frame carrying the members and deformable under relative move-

ment of the members when the latter are loaded.

14. A hopper comprising a sectional metallic sheathing, and flexible metallic suspension means supporting the same to permit the hopper to assume the form of a catenary curve in transverse vertical section.

15. A hopper comprising flexible walls, a

supporting frame, and suspension means carried by the frame having sufficient flexibility ¹⁰ under weight of the walls to cause the hopper to assume the form of a catenary curve in vertical cross section.

In testimony whereof I hereunto affix my signature this 28th day of July, 1924.

FRANK B. ALLEN.
